(57) CLAIM

The ornamental design for a ski mask, as shown and described.

DESCRIPTION

FIG. 1 is a perspective view of a ski mask showing the new design;

FIG. 2 is another perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines shown on the ski mask depict stitching, which does form a part of the claimed design.

1 Claim, 8 Drawing Sheets
